UNITED STATES PATENT OFFICE

FREDERIC D. COURTENAY, OF EAST ORANGE, NEW JERSEY, ASSIGNOR TO EMBOSOGRAF CORPORATION OF AMERICA, OF NEW YORK, N. Y., A CORPORATION OF NEW YORK

DESIGN FOR AN EASEL FRAME

Application filed February 14, 1930. Serial No. 34,555. Term of patent 14 years.

To all whom it may concern:

Be it known that I, FREDERIC D. COURTENAY, a citizen of the United States, and resident of East Orange in the county of Essex and State of New Jersey, have invented a new, original, and ornamental Design for Easel Frames, of which the following is a specification, reference being had to the accompanying drawing, forming a part hereof.

In the drawing, Fig. 1 is a perspective view of the easel frame showing my new design; and

Fig. 2 a side elevation thereof.

I claim:

The ornamental design for an easel frame, as shown.

FREDERIC D. COURTENAY.
